UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 17,861, dated November 1, 1887.

Application filed September 21, 1887. Serial No. 250,349. Term of patent 3½ years.

To all whom it may concern:

Be it known that I, MARY TURNER, of the city, county, and State of New York, have invented and produced a new and original Design for a Pattern of a Miss's Costume; and I do hereby declare that the engraved prints accompanying this specification convey to any one accustomed to using paper patterns a clear understanding of how a garment made up by

10 the pattern will appear.

The design shows a basque and a round walking-skirt. The skirt displays a side-plaited panel on the left side crossed by three straps, a front drapery that falls to the edge 15 of the skirt at the left side and exhibits a high drapery at the right side, where it folds over in a revers that tapers to a point at the center of the front, a full long back drapery that displays draping plaits in its side edges and loop-

ings to the skirt. The basque exhibits its 20 fronts meeting at their lower front corners and flaring toward the shoulders, revealing a fancy vest that has a full upper part, which disappears beneath the pointed upper edge of a smooth lower part, a close fitting back that 25 displays its skirt draped in loose folds between two points, a standing collar, and coat-sleeves with loose puffs above the elbows.

What I claim as my invention, and desire to 30 secure by Letters Patent, is—

The design for a miss's costume, as shown in the engraved prints accompanying this specification.

MARY TURNER.
